UNITED STATES PATENT OFFICE.

STEWART KAYE, OF EDINBURGH, SCOTLAND.

MACHINE FOR ERECTING WALLS OF BRICK AND THE LIKE.

Application filed February 2, 1924, Serial No. 690,160, and in Great Britain February 19, 1923.

This invention has reference to machines for erecting walls of brick and the like and comprises improvements in the machine for this purpose set forth in my prior patent specifications Nos. 119,331 and 134,296.

The object of my present invention is to provide a machine whereby the building of walls can be more expeditiously accomplished.

- 10 According to this invention the improved machine comprises, in combination, upright structures, a cross member (or members) extending between and joining said upright structures, and brick laying mechanism carried by and adapted to travel along said cross member, or cross members, the combination being such that the brick laying mechanism can be traversed to lay a course of bricks on each of four rectangular walls in succession.
- 15 Preferably the improved machine comprises in combination, two upright structures adapted to travel on rails, a horizontal structure or member joining said vertical structures, brick laying mechanism carried by and arranged to travel along said horizontal structure or member, and means for traversing the apparatus on its rails.
- 20 The arrangement and construction of the machine is such that the said vertical structure can be traversed on rails laid on the outside of two parallel walls to be built, the brick laying mechanism laying a course of brick on one of the walls during such movement, the brick laying mechanism then traversed on the horizontal structure to lay a course on the one of the end walls, the structures then again traversed on their rails in the opposite direction, a course of bricks being simultaneously laid on the other wall parallel to the rails, and the brick laying mechanism again traversed over the horizontal structure in the reverse direction thereby laying a course of bricks on the other end wall.
- 25 It will thus be seen that a course of bricks is laid on each of the four walls in succession, after which the traversed member is raised to permit of the next course to be laid.
- 30 My invention further consists in various improvements in the brick laying mechanism and the features of construction which will be hereafter described and pointed out in the claims.
- 35 In order that my invention will be properly understood I have hereunto appended seven explanatory sheets of drawings illustrating a preferred embodiment of my invention and

operating mechanism therefor and whereon:

Figure 1 is an elevation of the machine, a part of the traverse structure being shown broken away, but the length thereof will be at least such as the breadth of the building to be built necessitates.

Figure 2 is an end elevation of Figure 1 looking to the left.

Figure 3 illustrates an elevation of the brick laying mechanism, the view being taken from the other side of the machine to that shown in Figure 1.

Figure 4 is a sectional end elevation through the centre of the brick laying mechanism, Figure 3, looking to the right.

Figure 5 is a side elevation of the mortar tank looking to the left Figure 3.

Figures 6, 7 and 8 illustrate sectional plan view on the lines 6—6, 7—7, 8—8, Figure 3 respectively.

Figure 9 is a plan view of a ring at the top of the brick laying apparatus.

Figure 10 is an elevation of the gear which effects the various movements of the machine.

Figure 11 is a plan thereof.

Figure 12 is a plan view of part of the traversing mechanism not shown in Figure 11, and

Figure 13 is an end elevation of Figure 10 looking to the right.

Referring to the drawings:

A, A¹ are two vertical structures mounted to travel on rails 1, laid outside of and parallel to two opposite walls to be built.

B is a horizontal structure joining said vertical structures and C designates the brick laying mechanism carried by and arranged to travel along said horizontal structure B.

The vertical structures A, A¹ comprise two uprights suitably joined at their upper ends by girders 2 and provided with two wheels 3 at the base thereof. The transverse member B comprises two girders 4 provided with rails 7¹ and a rack 5.

On said structure B is mounted a carriage 6, the wheels 7 of which travel on said rails. A spur wheel 8 driven through suitable gearing to be hereafter described is carried by 105 the carriage and meshes with the rack 5.

The carriage 6 carries a receptacle comprising a framework 9 for holding two vertical columns of bricks 10 and below the framework is the brick laying mechanism, 110 comprising two frames 11 adapted to rotate on a horizontal axle 12.

Said frames 11 are provided with a number of flat faces 13 each having two spring actuated arms 14 for holding the bricks thereon.

The horizontally extending structure B is suspended at the four corners by ropes 15 which, at one side of the machine pass directly to a winding drum 16 located at the upper end of the vertical structure A, while the ropes supporting the other side of the structure pass over the pulleys 17 at the upper end of the structure A¹, and then to the drum 16.

A square vertical shaft 18 extends from end to end of the vertical structure A and on which is mounted a bevel wheel 19 capable of 15 a vertical movement thereon but incapable of a relative rotary movement.

Said bevel wheel 19 is in mesh with a bevel wheel 20 controlled by manually operated gearing 21 carried by the structure B. The 20 upper end of said vertical shaft is provided with a worm in mesh with the worm wheel 23 which through a train of gearing drives the shaft of the drum 16. Also extending vertically of each of said structures A, A¹ is 25 a square vertical shaft 24 on each of which is a bevel wheel 25 also capable of a relative axial movement but incapable of a rotary movement thereon. The lower end of each of said shafts is provided with a bevel wheel 30 26 in mesh with a bevel wheel 27 on the axle of which is a spur wheel 28.

The latter through an intermediate wheel 29, Figure 2, drives the spur wheel 30 which in turn meshes with the racks 31 laid parallel and on the outside of two walls to be built.

In mesh with the bevel wheels 25 are the bevel wheels 32 carried at the extremities of a horizontally extending square shaft 33 40 which is driven by gearing hereafter described.

A mortar tank 34 is carried by the frame supporting the brick laying mechanism and which supplies mortar to the wall as the 45 building proceeds.

The gearing whereby the necessary movement is imparted to spur wheel 8 to traverse the brick laying mechanism on the structure B, and to shaft 33 whereby the machine as a 50 whole can be moved on the rails, and also the brick laying mechanism, will now be described.

A motor 35, see Figures 10 and 11, carried by a frame projecting from the carriage 6 55 drives through a train of gearing 36, 36^a, 36^b, 36^c, 36^d and 36^e a shaft 37 on which are two loose bevel wheels 38 and 38^a. A sliding dog clutch 38^b, controlled by the hand lever 38^d, is adapted to engage with and drive either 60 of said bevel wheels. A third bevel wheel 38^b on the shaft 39 is in mesh with wheels 38 and 38^a, the three together forming a reversing gear for the shaft 39 on which is also keyed the spur wheel 39^a which through 65 the intermediate gear wheel 39^b, see Figure

13, drives the spur wheel 8 in mesh with the rack 5 and by which the brick laying mechanism is traversed on the structure B.

Also mounted on the shaft 37 is a bevel wheel 40 which through bevel wheel 40^a 70 drives the shaft 40^b. On the latter is a double clutch member 41, 41^a, arranged to engage with either clutch members 42, 42^a secured to the bevel wheel 42^b loose on the shaft 40^b. Said double clutch member is operated by a 75 hand lever 41^b through the links 41^c.

Those clutch members are so arranged that either of them can be brought into engagement with the corresponding clutch member on the bevel wheel but they are set one at 80 180° in advance of the other.

Said bevel wheel 42^b drives through a bevel wheel 44 a vertical shaft 44^a which at its lower end carries the spur wheel 44^b, see Figures 1, 9, 10 and 13. The latter is in mesh with 85 the large tooth wheel 44^c loose on a casting 44^d from which the brick laying mechanism is suspended. Also in mesh with this wheel is the pinion 45 on the vertical spindle 45^a, see Figure 4, which, through the bevel gearing 45^b, 45^c drives the horizontal shaft 46 on which is keyed the cam 47 by which the brick laying mechanism is operated and which will be hereafter described.

Also meshing with the spur wheel 36^e is 90 the spur wheel 48 on the shaft 48^a, on which are the loose spur wheels 49 and 50, see Figures 10 and 12.

Spur wheel 49 gears directly with a spur wheel 49^a on the transverse square shaft 33, see also Figure 1, while spur wheel 50 is in mesh with the intermediate pinion 50^a which in turn meshes with the spur wheel 50^b on the said square shaft. Both spur wheels 49^a and 50^b are capable of an axial movement on their 105 shaft. Also on the shaft 48^a is a clutch 51 controlled by lever 51^b and which can be operated to drive either of the spur wheels 49 or 50 according on the direction in which it is desired to rotate the square shaft 33. By 110 such means the direction of travel of the machine on its rails can be reversed as desired or by bringing the clutch to a neutral position, the structure can be brought to rest.

The casting 44^d, see Figure 10, from which 115 the brick laying mechanism is suspended is provided with a shoulder 44^e which rests on the correspondingly shaped shoulder 44^f of a ring 44^g secured by lugs 44^h to the carriage 6. Said casting 44^d is provided with four 120 notches 44ⁱ see also Figure 13 with one of which a latch 44^j is normally in engagement and by which the casting 44^d and brick laying mechanism is prevented from rotating under the action of the tooth ring 44^k.

Said latch is carried at the end of a rod 100, the upper end of which is connected to a bell crank 101, the vertical arm thereof being connected by the links 102 to the link 103. By pulling this latter the bell crank can be 130

operated to raise the latch 44^j clear of the notch 44ⁱ thereby permitting the rotation of the casting 44^d and brick laying mechanism with the tooth ring 44^e through an angle of 5 90°, the latch entering the next notch and locking the whole in position.

The framework 9 for holding the columns of bricks consists of a number of uprights arranged in such manner that bricks inserted 10 therein lie at a slight angle to the wall being built as indicated by Figure 6, the bottom bricks being supported at diagonally opposite corners on the projecting plates 52. Slightly above those projections are two 15 plates 53 notched as indicated to accommodate the bricks. The outer extremities of said plates are pivotally secured to the levers 54, 54^a pivoted at 55, 55^a respectively to the machine frame.

20 One of said levers 54 is connected to a helical spring 56, while the other end thereof abuts against an arm 57 pivoted to the machine frame at 57^a. Also pivotally secured to the machine frame at 58^a is a bell crank 25 lever 58 connected by means of a link 59 to the arm 57. Pivoted to the machine frame at 60^a is an arm 60 which carries a roller 61 and which is loaded by the two helical springs 62 maintained under tension, see Figures 3 30 and 4. To this arm is secured the two downwardly extending rods 63 which are connected to the rod 64 the lower extremity of which is connected to an arm 65 pivotally secured at 66 and connected by means of a 35 short link 67 to a frame or plunger 68 provided with four projections 69 and arranged to move vertically. 69^a are guide rods secured to the plunger and which slide in holes in guide blocks 69^b carried by the cross 40 bars 69^c.

On one of the rods 63 is a stop 70 which coacts with one of the arms 58^a of the bell crank lever 58. The rotation of the drum or frame of the brick laying mechanism is 45 obtained through a pinion 70 on shaft 46, spur wheel 70^a, sprocket wheel 70^b, chain 70^c and sprocket wheel 70^d, the latter being keyed on the shaft 12.

71 designates fixed rollers which co-act 50 with the spring loaded arms 14 so as to force them apart when about to receive a brick, while 72 designates fixed bars which co-act with the arms to force them apart when the brick retained thereby is about to be deposited 55 on the wall.

The mortar tank 34 is arranged to supply mortar to the upper side of the course of bricks previously laid.

The operation of the apparatus is as follows.

Assume the brick laying apparatus to be travelling as indicated by the arrow Figure 1.

When laying this course of bricks the motor is transmitting motion to the spur wheel 8

65 which, as it is in mesh with the rack 5,

causes the carriage 6 and brick laying mechanism to travel along the structure B. Once every brick length traversed cam 47 permits the rods 63 to descend under the action of the springs 62 which results in the frame or 70 plunger 68 carrying the projections 69 descending rapidly and knocking out the lowest bricks carried by the frame and deposit same on the wall, the bars 72 simultaneously forcing the arms holding such bricks slightly 75 apart. Simultaneously the descending rods permit the arm 58^b of the bell crank lever to effect a like movement so that the arm 57 moves outwards and the lever 54, 54^a turn about their pivots all under the action of the 80 spring 56. This results in the notched arms co-acting sharply with and dislodging the lowest brick in each column, which bricks fall on the frame 11 and are received by the upper spring loaded arms which are opened 85 to receive them by the action of the rollers 71.

As the cam rotates further the frame or plunger 68 is raised and the projection 70 co-acts with the arm 58^a to return same to its upper position, the notched plates 53 under 90 the action of the spring 56 being returned to the position shown in Figure 6 thereby allowing the pair of bricks supported thereby to fall on to the plates 52. In like manner, as the carriage 6 and brick laying device moves 95 along the wall, a pair of bricks is intermittently fed to the frame or drum and a pair of bricks simultaneously deposited on the wall.

It will be understood that the spur wheel 100 8 must move the carriage 6 a distance equal to one brick length plus the thickness of a mortar joint while the cams 47 makes exactly one revolution. When the end of the wall is reached clutch 38^c is operated to bring the 105 machine to rest and by means of the links 102 and 103 the latch 44^j is raised clear of the notch with which it is in engagement.

Here it would be explained that the resistance offered to the rotation of the cam shaft 110 46 is greater than that offered to the rotation of the brick laying mechanism bodily so that the casting 44^d then rotates with the tooth ring 44^e and carries pinion 45^b and brick laying mechanism with same; a pawl engaging 115 a ratchet wheel 103^a prevents the cam shaft rotating in the reverse direction.

When the brick laying mechanism has been turned through an angle of 90° the latch engages with the next notch thereby preventing 120 further rotation. Clutch 51 is then operated to drive the square transverse shaft 33. This shaft drives through the bevel wheels 32, 25, 26, 27 and spur wheels 28 and 29 the spur wheels 30 which being in engagement 125 with the racks 31 on the rails 1 traverse the machine as a unit along the rails. During this movement the brick laying mechanism deposits the bricks as formerly.

At the end of this wall clutch 51 is thrown 130

out of gear to bring the whole structure to rest, the laying mechanism again moving through an angle of 90° and clutch 38° is put into gear so as to drive the spur wheel 8 but 5 in the reverse direction so that the brick laying mechanism is traversed along the transverse member B and deposits a course of bricks on the other end wall. Again clutch 38° is thrown out of gear, the brick laying 10 mechanism rotated through an angle of 90° and clutch 51 again put into gear to drive the transverse square shaft and thereby move the apparatus bodily along the rails, the brick laying apparatus depositing a course of bricks 15 during its travel. At the end of this wall it is necessary to raise the transverse structure a distance equal to the height of a brick plus the thickness of a layer of mortar. This is accomplished by an attendant mounting the 20 platform 22 and operating the winding gear 21 whereby the ropes 15 are wound on the drum 16 and the whole transverse structure raised to the required extent.

The brick laying apparatus is rotated 25 through an angle of 90° but before proceeding to lay the next course it is necessary that the brick laying apparatus be moved a distance equal to half a brick length before commencing to deposit the second course. This 30 is effected by withdrawing the double clutch member 41, 41^a to a neutral position and, as the brick laying apparatus traverses the member B, slipping it into the clutch member 42 or 42^a which is half a revolution behind the 35 member previously in engagement therewith.

As shafts 39 and 40^b rotate one revolution per brick length, this results in the second course of bricks being laid in proper staggered relationship with the course immediately below.

In like manner the second and other courses are laid.

It will be noted that the brick laying mechanism always acts in timed relationship with the gear for traversing the brick laying mechanism and for traversing the apparatus bodily on its rails, the clutches being capable of engagement only at one point per revolution of their corresponding clutch members.

The bricks are fed to the receptacle 9 by an attendant who stands on a platform 99, Figure 12. In order to accelerate the process of building means are provided whereby the attendant is automatically supplied with bricks, as indicated diagrammatically, Figure 1. This may be accomplished by suspending a cage 99^a at the outer side of each of the upright structures A, A¹ the ropes supporting the cage passing over pulleys at the upper ends of said structures, pulleys carried by the structures B and then connected to carriage 6. The arrangement is such that as the said carriage with brick laying mechanism traverses structure B one of said cages is lowered 65 to be filled with bricks while the other one is

raised so that when the attendant reaches the end of his travel he is provided with a cage of bricks to feed to the brick laying device.

As the cross member is raised the ropes automatically become shortened and they are attached on roller having driving gear by which they are rotated to allow of the slack being taken up.

While the bricks are being laid as aforesaid the mortar in the tank 34 is discharged therefrom by means of a grooved roller 74 rotated by means of a chain drive 75 from the sprocket wheel 76 on the axle 12.

Spring loaded scraping devices 77 dislodge the mortar from the grooves as the roller rotates and deposits same on endless bands 78 driven through a train of gearing 79 from a spur wheel 80 fast on the axis of the roller. A scraping device 81 dislodges the mortar from the bands and deposits same on the wall.

Secured to projecting brackets 82 on the frame is a cross shaft 83^a on which are secured an arm 84 and two arms 85 one at each side of the machine. Arm 84 carries a roller 84^a at its lower end, while the extremity of each of the arms 85 is connected by means of a rod 86 to a lever 87 pivoted at 88 and carrying a roller and beveling or skimming bar 89. A helical spring 90 is connected to the levers 87 and frame.

The action of such device is as follows: After each brick has been laid and the machine has traversed one third the length of a brick the cam through the aforesaid mechanism permits the scraper to be moved towards the last laid brick under the action of the spring 90, some mortar being scraped up in its travel and deposited against the exposed end of the brick. Further said bar pushes the bricks up against the adjacent brick thereby consolidating the wall being built.

As shown in Figures 3 and 8 guiding arms 91 are carried by the brick laying apparatus and which serve to ensure that each brick is brought into alignment as the courses are laid. To permit the brick laying apparatus to be moved through an angle of 90° as aforesaid said guide arms must be raised clear of the wall. This is accomplished by mounting the arms on the pivoted parallel arms 92 and connecting same to a vertical rod 93 by raising which the guide arms are likewise raised so as to permit the partial rotation of the brick laying device. It is desirable that the mortar in the tank 34 be kept in a state of agitation.

In the arrangement shown this is effected by means of a stirring blade 94 (see Fig. 5) carried by arms 94^a on a cross bar keyed to a shaft 94^b on which is secured an arm 95 (see also Fig. 3) the latter being connected by means of a rod 96 with an eccentric 97 on the shaft of roller 74.

By such means the mortar is kept in a continual state of agitation when the apparatus is in operation.

The structure by which the brick laying apparatus is supported may be modified. For example at each side of the building to be built two vertical structures may be erected 5 each provided with horizontally extending structures arranged parallel to each other and to two of the four walls to be built. A cross member extends between and joins the horizontally extending structures and is arranged 10 to travel along same. The brick laying mechanism is mounted to travel along said cross member.

In operation the brick laying mechanism first travels along the cross member and lays 15 a course of bricks on one of the walls, the cross member is then traversed along the said horizontally extending structures, the brick laying mechanism depositing a course of bricks on one of the side walls. The brick laying mechanism is then again traversed of 20 the cross member, and again the latter traversed on the horizontally extending structures, a course of bricks being deposited on the other two walls during such movements.

25 Such arrangement is in fact substantially the same as that described and illustrated with the exception that instead of traversing the vertical structures A, A¹, the cross member B is traversed on horizontally extending members or structures carried by the vertical structures. Or again the apparatus may comprise a four sided framework supported horizontally on vertical structures, and the brick laying mechanism supported 30 by and arranged to travel along each of the four sides of the framework in succession, a course of bricks being laid on each of the four walls during such movement.

What I claim is:—

40 1. A machine for erecting walls of brick and the like comprising in combination upright structures, a cross member extending between and joining said upright structures, said member being adapted to straddle two parallel walls being built, brick laying mechanism carried by and adapted to travel on 45 said cross member, and means whereby the brick laying mechanism may be traversed to lay a course of brick on each of four rectangular walls or cross walls in succession.

50 2. A machine for erecting brick walls comprising movable upright structures, a cross member interconnecting said structures and arranged to straddle two parallel walls being built, brick laying mechanism movably mounted on said cross member, and means whereby said brick laying mechanism as well as the machine as a whole may be actuated to lay a course of brick in succession on a 55 plurality of angularly disposed walls.

60 3. A machine for erecting walls of brick and the like comprising in combination, two upright structures and adapted to straddle two parallel walls being built, adapted to 65 travel on rails laid on the outside of two par-

allel walls to be built, a horizontal structure extending between and joining said vertical structures, brick laying mechanism carried by said horizontal structure, means for traversing said brick laying mechanism along 70 the horizontal structure, means for traversing the machine on its rails, and means for raising and lowering the horizontal structure with respect to the upright structure.

75 4. A machine for erecting walls of brick and the like comprising in combination two upright structures adapted to travel on rails, a horizontal structure extending between and joining said vertical structures, brick laying mechanism carried by said horizontal structure, means for traversing said brick laying mechanism along said horizontal structure, means for traversing the machine along its rail, and means for actuating the brick laying mechanism in timed relationship with 80 the travel of the machine on its rails and with the travel of the brick laying mechanism along the horizontal structure.

85 5. A machine for erecting walls of brick and the like comprising in combination two upright structures adapted to travel on rails, a horizontal structure extending between and joining said vertical structures, a carriage to travel on said horizontal structure, brick laying mechanism suspended from said carriage, means for traversing said carriage along said horizontal structure, means for rotating said brick laying mechanism in a horizontal plane with respect to the carriage, means for traversing the brick laying mechanism in timed relationship with the travel of the carriage and with the travel of the machine.

90 6. A machine for erecting walls of brick and the like comprising in combination two upright structures adapted to travel on rails, a horizontal member extending between and joining said upright structures, brick laying mechanism carried by said horizontal member and comprising a receptacle for a column, or columns, of bricks, means to support the lowest brick of each column, a rotatably mounted frame located below said receptacle, means to dislodge the lowest brick of each column so that it falls on to the said frame, means for holding the said brick on the frame, means for rotating the frame and means for ejecting the brick from said frame on to the wall being built, means to traverse said brick laying mechanism along the horizontal members, means to traverse the machine on its rails, means to operate the brick laying mechanism in timed relationship with its travel along said horizontal members and with the travel of the machine, and means to raise and lower said horizontal member with brick laying mechanism.

100 7. A machine for erecting walls of brick and the like comprising in combination two upright structures adapted to travel on rails,

- a horizontal member extending between and joining said upright structures, brick laying mechanism carried by said horizontal member, means for rotating said receptacle in a 5 horizontal plane with respect to the carriage and comprising a receptacle for a column, or columns of bricks, means to support the lowest brick of each column, a rotatably mounted frame located below said receptacle, 10 means to dislodge the lowest brick of each column so that it falls on to the said frame, means for holding the said brick on the frame, means for rotating the frame, and means for ejecting the brick from said frame 15 on the wall being built, means to traverse said brick laying mechanism along the horizontal member, means to traverse the machine on its rails, means to operate the brick laying mechanism in timed relationship with 20 the travel along said horizontal member and with the travel of the machine, and means to raise and lower said horizontal member with brick laying mechanism.
8. A machine for erecting walls of brick 25 and the like comprising in combination two upright structures adapted to travel on rails, a horizontal member extending between and joining said upright structures, brick laying mechanism carried by said horizontal 30 member and comprising a receptacle for a column, or columns of bricks and rotatably mounted frame below said receptacle, means for traversing said brick laying mechanism along the horizontal members, means to 35 traverse the machine along its rails, a cam, means driven in timed relationship with the travel of the brick laying mechanism with the travel of the machine to operate said cam, and means actuated by said cam to dislodge 40 the bricks from the receptacle on to said frame and from the frame on to the wall being built.
9. A machine for building walls of brick 45 and the like comprising two upright structures adapted to travel on rails, horizontal structures extending between and joining said upright structures, means for raising and lowering said horizontal structures, means for traversing the machine on its 50 rails, a carriage on said horizontal member, a receptacle for a column, or columns of bricks carried by said receptacle, a rotatably mounted frame below said receptacle, means for rotating said receptacle and frame in a 55 horizontal plane with respect to the carriage and means arranged to operate in timed relationship with the travel of the machine and carriage and to eject the bricks from the receptacle on to the frame, and from the 60 frame on to the wall being built.
10. A machine for erecting walls of brick and the like comprising in combination two

upright structures adapted to travel on rails, a horizontal structure or member extending between and joining said vertical structures, brick laying mechanism carried by said horizontal structure or member, means to supply mortar to the previously laid course, means to push each brick as it is laid toward the previously laid brick; means for traversing said brick laying mechanism along said horizontal structure or member, means for traversing the machine along its rails, and means to actuate the brick laying mechanism in timed relationship with the travel of the machine on its rails and with the travel of the brick laying mechanism along the horizontal structure or member.

11. A machine for erecting walls of brick and the like comprising in combination two upright structures adapted to travel on rails, a horizontal structure or member extending between and joining said vertical structure, brick laying mechanism carried by said horizontal structure or member, a mortar tank, 80 an endless band carried by the brick laying mechanism to receive the mortar and deliver same to the previously laid course, means to push each brick as it is laid toward the previously laid brick, means for traversing said brick laying mechanism along said horizontal structure or member, means for traversing the machine along its rails and means to actuate the brick laying mechanism in timed relationship with the travel of the machine on its rails and with the travel of the brick laying mechanism along the horizontal structure or member.

12. A machine for erecting walls of brick and the like comprising in combination two upright structures adapted to travel on rails, a horizontal member extending between and joining said upright structure, brick laying mechanism carried by said horizontal member and comprising a receptacle for a column, or columns, of bricks, means to support the lowest brick of each column, a rotatably mounted frame located below said receptacle, means to dislodge the lowest brick of each column so that it falls onto the said frame, means for holding the said brick on the frame, means for rotating the frame and means for ejecting the brick from said frame on to the wall being built, a mortar tank, an endless band carried by the brick laying mechanism to receive the mortar and deliver same to the previously laid course, means to push each brick as it is laid toward the previously laid brick, means to traverse said brick laying mechanism along the horizontal members, and means to traverse the machine on its rails.
